SPLINE INDICATOR GAGE

London T. Morawski, Detroit, Mich., assignor of one-half
to John J. Parker, Van Dyke, Mich.

Filed Jan. 13, 1966, Ser. No. 590

Term of patent 14 years

(Cl. D52—6)

FIG. 1

FIG. 2

FIG. 1 is a perspective view of a spline indicator gage embodying my new design.

FIG. 2 is a side elevational view thereof.

FIG. 3 is a top view thereof.

FIG. 4 is an end view of the gage as viewed from the end opposite the handle.

FIG. 5 is an end view as viewed from the handle end of the gage.

FIG. 6 is a bottom plan view thereof.

The dominant features of my design reside in the portions shown in full lines.

The undisclosed side of the gage is substantially the same in appearance as the side shown.

I claim:

The ornamental design for a spline indicator gage, substantially as shown and described.
